Primary Examiner—Wallace R. Burke
Assistant Examiner—Robin V. Taylor[57] **CLAIM**

The ornamental design for the recycle bin, as shown and described.

DESCRIPTION

FIG. 1 is a perspective view of the recycle bin showing my new design;

FIG. 2 is a front end elevation thereof;

FIG. 3 is a back end elevation thereof;

FIG. 4 is a side elevation thereof, the opposite side is a mirror image;

FIG. 5 is a vertical sectional view of line 5—5 of FIG. 4; and,

The undisclosed bottom is flat except for the inclusion of six rounded beads as noted in FIG. 2 which extend the entire length of the bottom.
